O. REHME

STOPPING MECHANISM FOR INTERNAL COMBUSTION ENGINES

Filed July 12, 1924

UNITED STATES PATENT OFFICE.

OTTO REHME, OF MOSLING, WISCONSIN.

STOPPING MECHANISM FOR INTERNAL-COMBUSTION ENGINES.

Application filed July 12, 1924. Serial No. 725,659.

To all whom it may concern:

Be it known that I, Otto REHME, a citizen of the United States, and resident of Mosling, in the county of Oconto and State of Wisconsin, have invented certain new and useful Improvements in Stopping Mechanism for Internal-Combustion Engines; and I do hereby declare that the following is a full, clear, and exact description thereof.

10 This invention relates to stopping mechanism for internal combustion engines.

In a number of places internal combustion engines are employed as for instance on the farm, in dairies, cheese factories and other 15 places where they are required to perform a certain amount of work and, thereafter, are stopped at predetermined times by an attendant. This necessitates the presence of an attendant to cut off the fuel and the 20 lubricating oil and needlessly increases the expense of operation.

This invention is designed to overcome the above noted defects, and objects of such invention are to provide a stopping mechanism 25 for internal combustion engines which may be set at a predetermined time to both cut off the fuel supply and the lubricating oil.

Further objects are to provide a stopping mechanism which may be readily installed 30 upon existing types of engines with a minimum of change, which may be cheaply and simply produced, and which is free from complicated and elaborate mechanism.

An embodiment of the invention is shown 35 in the accompanying drawings, in which:—

Figure 1 is a rear view of a standard form 40 of internal combustion engine equipped with the stopping mechanism.

Figure 2 is a fragmentary side elevation 45 of the structure shown in Figure 1.

Figure 3 is a fragmentary plan view of the 50 upper end of the rod and oiler, such view being partly in section.

The internal combustion engine comprises 55 a cylinder whose head is indicated at 1 and a hopper 2. This type of engine is usually provided with an oiler 3 at its upper end which is controlled by means of a lever 4 pivoted thereon, such lever being adapted to 60 cut off the oil when in the horizontal position shown in Figure 2, and to allow flow of the lubricating oil when it is in a vertical position. The engine is further equipped with a starting reservoir provided with a fuel 65 control valve having a manipulating disk 6.

This fuel control valve is the normal operating valve for the engine.

In applying the stopping mechanism to the engine a shelf 7 is provided preferably formed of sheet metal and is equipped with 65 downwardly extending lugs 8 which are bolted to the engine in any convenient manner as by means of the bolts 9 in the engine head 1 although it is to be understood that this device may be bolted at any desired 70 point. The shelf rigidly carries a saddle 10 within which an alarm clock 11 is seated and secured. This alarm clock is provided with the usual winding key 12 for the time mechanism. The other winding key for the 75 alarm mechanism is replaced by means of a disk or wheel 13 which is screwed in place as a substitute for the winding key. This wheel is provided with a pin 14 for a purpose hereinafter to appear.

The disk 6 for controlling the fuel is drilled and is equipped with a pin 15. These pins 14 and 15 are connected by means of a link 16 so that motion from the wheel 13 may be transmitted to the control valve. A 80 bracket 17 is adjustably secured to a portion of the engine for instance the reservoir 5, and carries one end of a tension spring 18. The other end of the tension spring is secured to the lower end of the link 16, as 85 shown in Figure 2. The link 16 rigidly carries a diagonally upwardly extending arm 19 which terminates at its upper end in a laterally projecting horizontal portion 20. This horizontal portion 20 is carried by 90 means of a slotted guide 21 secured to the oiler 3, as shown in Figures 1 and 3.

An elongated loop 22 is formed of a portion of the horizontal extension 20 and is adapted to manipulate the lever 4 of the 95 oiler, as will be described later.

The operation of the apparatus is as follows:—The link 11 and the wheels or disks 6 and 13 are turned in a clockwise direction, as in Figure 2, to open the fuel 100 valve. This winds the alarm mechanism a little tighter, it being understood that the alarm mechanism is kept in a wound condition. The pins 14 and 15 are then positioned on the right hand side of the centers 105 of the disks 6 and 13. The arm 19 is moved upwardly and forwardly positioning the loop 22 directly over the lever 4. The lever 4 is then elevated and the engine is in running 110 condition with a supply of fuel and oil 110

furnished thereto. The alarm is set at the desired point and when the alarm is released by the clock 11, the wheel or disk 13 rotates thus rotating the disk 6. When, however, 5 the pin 15 of the disk 6 is in its uppermost dead center position, the spring 18 operates to pull the pin 15 passed dead center, and thus permits the transmission of rotary motion from the wheel 13 to the wheel or 10 disk 6 throughout a large portion of a revolution. The cut off valve is thus closed at the desired time by rotation of the disk 6. In addition to this, the loop 22 moving downwardly and rearwardly rocks the lever 4 15 into its horizontal position, as shown in Figure 4 and thus cuts off the lubricating oil.

It will thus be seen that an automatic engine stopping mechanism has been provided, which may be most readily attached to standard types of internal combustion engines, and which will cut off both the fuel and the oil at a predetermined time without requiring the attention of an operator.

20 It will further be seen that the device is simple, inexpensive, compact and readily applied to existing types of internal com-

bustion engines with a minimum change thereof.

Although the invention has been described 30 in considerable detail, it is to be understood that the invention may be variously embodied and is, thereof, to be limited only as claimed.

I claim:

35 The combination of an internal combustion engine having a fuel control valve provided with a disk, an alarm clock secured to said engine and having a disk operated by the alarm mechanism, pins in said disks, 40 a substantially vertical link connecting said pins, a spring secured to one end of said link and extending at right angles thereto adjacent said valve control, an arm extending laterally from said link and rigidly attached thereto and provided with a looped outer end, an oiler carried by said engine, and a control lever for said oiler adapted 45 to be positioned within the looped end of said rod.

50 In testimony that I claim the foregoing I have hereunto set my hand at Mosting, in the county of Oconto and State of Wisconsin,
OTTO REHME.
